TOY HOUSE CONSTRUCTION

Joseph Brunetti, Carlstadt, N. J., assignor to Columbia Protektosite Company, Inc., Carlstadt, N. J., a corporation of New Jersey

Application April 9, 1948, Serial No. 19,929

4 Claims. (Cl. 46—12)

1

This invention relates to miniature house constructions, and more particularly is directed to an easily erected model, display, toy, or play house structure having readily accessible room spaces simulating actual or proposed houses adapted to be furnished with portable miniature size furniture, interior decorations and the like.

Among the objects of the invention is to provide toy or play house constructions of the character described which shall comprise few and simple parts that are readily assembled to provide a structure simulating in miniature form actual or proposed rooms of households or apartments, which shall be made portably collapsible and easily erected, which shall be adapted to be furnished with portable miniature size furniture, interior decorations and the like, which shall be cheap to manufacture yet have aesthetic appeal, which shall be practical and efficient to a high degree in use.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawing in which is shown one possible illustrative embodiment of this invention:

Fig. 1 is a cross sectional view taken centrally through a toy or play house constructed to embody the invention.

Fig. 2 is a top plan view of the improved toy or play house shown in Fig. 1.

Figs. 3 and 4 are plan views of the upper and lower floors, respectively, of the improved toy or play house as seen from lines 3—3 and 4—4, respectively, in Fig. 1, and

Figs. 5 and 6 are side elevational and front views, respectively, of the improved toy or play house shown in Figs. 1 and 2.

Referring in detail to the drawing, 10 denotes a toy play house of circular configuration constructed to embody the invention.

Preferably house 10 is made of any suitable lightweight metallic or non-metallic sheet material and for cheapness may be made principally of cardboard lithographed or printed if desired to imitate the wall, ceiling and/or floor coverings and decorations and the like.

Said house 10 is seen to comprise a flat horizontally disposed circular shaped base 11, which provides a first floor, an intermediate circular

2

flat shaped horizontally disposed member 12 which provides a second floor spaced from base 11, and a flat segmentary shaped horizontally disposed top 13 which provides a roof spaced from said member 12. As shown in Figs. 1, 2, 3 and 4, said base 11, member 12 and roof 13 are assembled in spaced superimposed relation to correspond in proportions to the heights with relation to the floor area of the various simulated rooms or apartments. Said base 11, member 12 and roof 13 are demountably retained in assembly by suitable means, such as a plurality of spaced apart upstanding stanchions or rods 14 extending therethrough close to the peripheries thereof and a similar center rod 15 uniformly positioned with respect to said rods 14, said rods 14 being positioned in parallel alignment and may be set radially at about 120° apart.

In the construction in Figs. 1, 3 and 4, said rods 14 and 15 may each be provided with spaced tubes or sleeves 14a and 15a, respectively to retain the member 12 and roof 13 in secured horizontal level alignment with base 11. Said rods 14 and 15 each may have shallow headed lower ends 14b and 15b, respectively, which are recessed flush into the bottom side 11a of base 11. The upper free ends of each of said rods 14 may be threaded as at 14c and provided with a suitable finial such as blind clamping nuts 14d, and rod 15 may be likewise threaded as at 15c and provided with screw clamping finial 15d shaped to simulate a radio antenna.

Similarly secured in upright positions between base 11 and member 12, are partitions 16, 17 and 18 which divide the space therebetween into chambers or room sections 20, 21 and 22, section 20 having an alcove portion 20a in which are stairs 23 and center rod 15 with tube 15a extending therethrough, as is clear from Fig. 4.

Said portion 16 may be made with an offset extension 16a forming a wall of said alcove portion 20a and a doorway or opening 16b communicating room section 20 with room section 21. Likewise partitions 17 and 18 may each be provided with suitably positioned doorways or openings 17a and 18a, respectively, communicating room section 21 with 22, and room section 22 with 20, respectively.

If desired, room section 20 may be furnished with miniature furniture (not shown) as an enclosed front porch or living room, room section 21 rear, as a kitchen, and room section 22 side, as a dining room. The walls of said partitions, room ceilings, floor surfaces and interior house trim may be appropriately imprinted, lithographed or

otherwise decorated to conform to the furnishing of the character of the room to be simulated in the well understood manner.

Said partitions 16, 17 and 18 may be interlocked along their respective edges with the base 11 and member 14 by any suitable means of simple construction, such as tongue and slot attachments 24. Similarly secured in upright position between the member 12 and the roof 13 are second floor outer wall portions 25, and partitions 26, 27 and 28' which divide the space therebetween into room sections 29, 30, and 31 and an open or uncovered space 33 over portion 12a of member 12 extending on the exterior of wall portion 25. A floor opening 32a of hallway 32 formed between said partitions 26, 27 and 28 leads down said stairs 23, said hallway 32 having center rod 15 with tube 15a extending therethrough as is clear from Fig. 3. Wall portion 25 having an opening or doorway 25a communicating with the hallway 32 may have exterior surface 25b of said wall 25 above the upper floor decorated to simulate outer wall building construction, such as brick, stucco or shingle. The roof 13 may be extended beyond said wall 25a as at 13a, to provide an eave and to leave uncovered said member portion 12a to simulate a segmentary shaped open porch as seen from Figs. 1, 2, 3 and 5.

The stairway 23 may be held in place by conventional means, such as, by attachment to members 11 and 12.

Said partitions 26, 27 and 28 may be provided with a door opening 26a, 27a and 28a, respectively, communicating with hallway 32, and may also be firmly set in place by suitable means such as tongue and slot attachment 24.

Room section 29, 30 and 31 may have the walls, floors and ceilings decorated to conform to predetermined interior decorations, and furnished with miniature furniture as for example, a master bedroom nursery and another bedroom or sun parlor, respectively.

The house 10 may have no opaque exterior upright walls other than provided by wall portion 25. However to provide a simulated front entrance, a sheet 34 may be extended to partially encircle the lower floor between the two spaced apart stanchions 14. Said sheet 34 may be formed of a flexible transparent material such as cellophane or other plastic and may have imprinted or lithographed thereon a picture of a doorway 34a, directly in alignment and under the doorway 25a. Suitable clip fasteners 35 may be provided on the ends of sheet 34 for engaging stanchions 14. Said sheet 34 being of a height to extend a short distance above the portion 12a and circling the same as is clear from Figs. 1, 4, 5 and 6.

If desired a second similar sheet 36 of transparent material may be provided to encircle the house extending from the base 11 to the roof 13 and about the sides and rear of the house as indicated in Fig. 4. Said second sheet 36 may also be secured by suitable spring clips (not shown) similar to clips 35 to the stanchions 14 or sheet 36 may be of a resilient material preformed in arcuate shape of less diameter than that of the house. By flexing the resilient sheet to an increased diameter the latter may readily be positioned about stanchions 14 and upon release thereof will grippingly engage said stanchions 14 as is clear from Fig. 4 thereby being retained in position without requiring any fastening means whatsoever.

In practicing the invention all the parts may

be supplied in a "knockdown" condition in a box and may be readily assembled to form the toy or play house 10 shown in the drawing and described above. The tongue and slot connections 24 of each of the partitions with a base 11, member 12 and roof 13 form a rigid assembled structure when clamped in position by the rods 14 and 15. With sheet material 34 and 36 removed all the rooms are accessible from the exterior so that miniature furniture (not shown) can be placed about the floors of the different rooms to suit any desired artistic arrangement, such as a simulated kitchen, livingroom, diningroom, bedroom and the like.

The floor surfaces of base 11 and member 12 may either have imprinted thereon designs simulating floor covering or if desired actual cloth or other sheet material may be readily placed or attached for such purposes. Likewise, the partition surfaces and ceilings which form walls for the various rooms or apartments may have imprinted thereon suitable wall paper decorations, framed pictures, mirrors and the like.

The toy house 10 thus formed can be easily erected to give readily accessible room spaces always visible for simulating actual and proposed arrangements when furnished with portable miniature size furniture and decorations and the like to conform therewith, and thus provides a toy or play house of particular interest and appeal to children and to grownups who may use the same to more clearly visualize various arrangement of rooms.

It is obvious that instead of using a single intermediate circular flat shaped horizontally disposed member 12 to provide a second floor spaced from the base that additional similar horizontally disposed members like member 12 may be interposed in spaced relation to form a house construction of a plurality of stories.

It will thus be seen that there is provided a miniature house construction of the character described in which the several objects of this invention are achieved and which are well adapted to meet the conditions of practical use.

As various possible embodiments might be made of the above invention, and as various changes might be made in the embodiment above set forth, it is to be understood that all matters herein set forth or shown in the accompanying drawing are to be interpreted as illustrative and not in a limiting sense.

Having thus described my invention, I claim as new and desire to secure by Letters Patent:

1. A knockdown toy play house construction of the character described suitable for furnishing with miniature furniture comprising a plurality of horizontally disposed flat members positioned in separated superimposed relation to form ground and intermediate floors and a roof, a plurality of spaced apart stanchions upstanding from a peripheral portion of said ground floor member removably supporting said other members in said separated relation, a center stanchion upstanding from said ground floor member uniformly spaced from said peripheral stanchions for removably supporting midsections of said members and roof, detachable partitions extending between said members for dividing spaces therebetween into room sections each with a full opening communicating with the exterior to permit full view of and access to each room section, a flexible sheet of transparent material having clips thereon for engaging two of said peripheral stanchions, said sheet being positioned to serve as an outer wall

portion for one of said room sections and formed with a simulated front door for said house construction, at least two of said members being circular in shape, said roof being segmentary shaped to provide an open deck space on the underlying intermediate circular member, two of said stanchions being positioned in an aligned relation with respect to the straight side of the roof member, and an exterior wall partition extending from the underside of the roof member to the deck between said two stanchions.

2. A knockdown toy play house construction of the character described suitable for furnishing with portable miniature furniture comprising a plurality of horizontally disposed flat members positioned in separated superimposed relation to form ground and intermediate floors and a roof, a plurality of spaced apart stanchions upstanding from a peripheral portion of said ground floor member removably supporting said other members in said separated relation, a center stanchion upstanding from said ground floor member uniformly spaced from said peripherally positioned stanchions for removably bracing midsections of said members and roof, detachable partitions vertically disposed to engage between said members for bracing regions of the latter between said stanchions and extending to the periphery of said members for dividing spaces therebetween into room sections each with a full opening communicating with the exterior to permit full view of and free access to each room section, a flexible sheet of transparent material having clips thereon for engaging two of said peripheral stanchions, said sheet being formed with a simulated door for said house construction positioned to serve as an outer front wall, at least two of said members being congruently shaped, said roof being of smaller area than each of said congruently shaped members for exposing an underlying member to provide an open deck on the latter, said stanchions each including a rod fitted with sleeves threaded coaxially therewith to provide combination spacers and supports, and clamping means carried by the rods for demountably retaining the stanchions, rods and sleeves with the members as a rigid structure.

3. A knockdown toy play house construction of the character described suitable for furnishing with portable miniature furniture comprising a plurality of horizontally disposed flat members positioned in separated superimposed relation to form ground and intermediate floors and a roof, a plurality of spaced apart stanchions upstanding from a peripheral portion of said ground floor member removably supporting said other members in said separated relation, a center stanchion upstanding from said ground floor member uniformly spaced from said peripherally positioned stanchions for removably bracing midsections of said members and roof, detachable partitions vertically disposed to engage between said members for bracing regions of the latter between said stanchions and extending to the periphery of said members for dividing spaces therebetween into room sections each with a full opening communicating with the exterior to permit full view of

and free access to each room section, a flexible sheet of transparent material formed with a simulated door for said house construction extending between two of said peripherally positioned stanchions to serve as an outer front wall, clip fastening means for securing said sheet to said peripheral stanchions so constructed and arranged to permit ready access from the exterior for arrangement of miniature furniture to all the room sections with the sheet in said outer front wall position.

4. A knockdown toy play house construction of the character described suitable for furnishing with miniature furniture comprising a plurality of horizontally disposed flat members positioned in separated superimposed relation to form ground and intermediate floors and a roof, a plurality of spaced apart stanchions upstanding from a peripheral portion of said ground floor member removably supporting said other members in said separated relation, a center stanchion upstanding from said ground floor member uniformly spaced from said peripherally positioned stanchions for removably supporting midsections of said members and roof, detachable partitions extending between said members for dividing spaces therebetween into room sections each with a full opening communicating with the exterior to permit full view of and access to each room section, at least two of said members being circular in shape, said roof being segmentary shaped formed with a straight side to provide an open front deck space on the underlying intermediate circular member, two of said stanchions being positioned in an aligned relation with respect to said straight side, an exterior wall portion extending from an underside of the roof member to the deck between said two stanchions, a flexible sheet of transparent material formed with a simulated front door for said house construction extending between said two aligned peripheral stanchions in a vertical direction between said ground and intermediate floors to serve as an outer front wall thereat, clip fastening means for securing said sheet to said peripherally positioned stanchions so constructed and arranged to permit ready access from the exterior to all the room sections for arrangement of miniature furniture when said sheet is positioned to serve as said outer front wall.
